US00D439898S

(12) **United States Design Patent** (10) Patent No.: **US D439,898 S**
Ober et al. (45) Date of Patent: ** Apr. 3, 2001

(54) **CONTOURED HOUSING**

(75) Inventors: **Lawrence R. Ober**, Pineville; **Brian V. Conti**, Matthews; **Michiel R. Ausems**; **Scott C. Cardais**, both of Charlotte, all of NC (US)

(73) Assignee: **Hand Held Products, Inc.**, Charlotte, NC (US)

(**) Term: **14 Years**

(21) Appl. No.: **29/098,187**

(22) Filed: **Dec. 22, 1998**

Related U.S. Application Data

(63) Continuation of application No. 29/084,781, filed on Mar. 10, 1998, which is a continuation-in-part of application No. 29/079,167, filed on Oct. 27, 1997, now Pat. No. Des. 400,872, which is a continuation of application No. 29/060,284, filed on Sep. 6, 1996, now Pat. No. Des. 392,282, which is a continuation-in-part of application No. 29/051,739, filed on Mar. 18, 1996, now abandoned.

CLAIM

The ornamental design for a contoured housing, as shown and described.

DESCRIPTION

FIG. 1 is a perspective view of a contoured housing showing a first embodiment of our new design;

FIG. 2 is a top plan view thereof;

FIG. 3 is a left side elevational view, the right side being a mirror image thereof;

FIG. 4 is a front elevational view thereof;

FIG. 5 is a rear elevational view thereof;

FIG. 6 is a bottom plan view thereof;

FIG. 7 is a perspective view of a contoured housing showing a second embodiment of our new design;

FIG. 8 is a left side elevational view, the right side being a mirror image thereof;

FIG. 9 is a front elevational view thereof;

FIG. 10 is a rear elevational view thereof; and,

FIG. 11 is a bottom plan view thereof.

The top view of the second embodiment shown in FIG. 7 is like FIG. 2.

The broken lines shown herein are for illustrative purposes only and form no part of the claimed design.
